United States Patent Office

Des. 201,539
Patented July 6, 1965

201,539

LITURGICAL VESTMENT

Jane E. Maiarana, 178 Laird Ave., Buffalo, N.Y.

Filed Dec. 7, 1964, Ser. No. 82,940

Term of patent 14 years

(Cl. D3—26)

FIG. 1 is a front elevational view of a liturgical vestment showing my new design; and

FIG. 2 is a rear elevational view thereof.

I claim:

The ornamental design for a liturgical vestment, substantially as shown.
